FIG. 7.

INVENTOR
BLAINE F. GOODRICH.
By Thomas L. Ryan
ATTORNEY.

UNITED STATES PATENT OFFICE.

BLAINE F. GOODRICH, OF MUNCIE, INDIANA.

TABLE.

Application filed August 2, 1927. Serial No. 210,057.

This invention relates to improvements in wall tables.

Objects of the invention are to provide a device of this kind which is simple in construction, easy to install and to use, and which occupies relatively small space when collapsed. Some of the more specific purposes of the invention are to provide a wall table which is rugged and serviceable for general uses; practicable to handle in merchandising, and which is economical of manufacture, and not liable to become impaired or to get out of order.

The objects of my invention are accomplished, and the advantages for which it is intended, are attained, by the new construction, combination and arrangement of parts described in the following specification, and illustrated in the accompanying drawings.

20 The invention is defined in the appended claims.

The several parts of the invention are identified by suitable characters applied to them in the different views in the drawings,—in 25 which:

Figure 1 is a front view of my improved wall table as it appears in readiness for use.

Figure 2 is plan view of the invention as shown in Figure 1, a portion of the table top 30 being broken away.

Figure 3 is a transverse sectional view taken on the line 3—3 and as seen in the direction of the arrow in Figure 1.

Figure 4 is a transverse enlarged sectional view taken on the line 4—4 and as seen in the direction of the arrow in Figure 1.

Figure 5 is an end view of the invention showing the positions of the several parts in the folded or collapsed status.

40 Figure 6 is a top plan view of Figure 5; and

Figure 7 is a sectional view on the line 7—7 in Figure 3.

My invention contemplates the providing 45 of a back plate or board of suitable length and thickness and of neat appearance, adapted to be secured to a wall or to any other kind of support or object, a table top, hinge connections between the table top and the back plate, the axes of such hinge connections being at a predetermined distance from the face of the

back plate, a support bracket hinged on the underside of the table top at an angle to and at a distance from the axes of said hinge connections not less than the thickness of the 55 support bracket, and an abutment element on the face of the back plate to be engaged by the vertical leg of said support bracket when the table top is in the extended position.

The table top, back plate, and bracket may 60 be made of pressed metal or of wood, preferably the latter, and the dimensions and general formation of these parts may be varied in accordance with such special uses for which the table may be intended. In the present 65 embodiment, the invention is shown in the form and size which is suitable for general use in the household, work shop or office, the wooden back plate A being about thirty four inches in length. A practicable form of hinge 70 connection between the back plate and table top, may consist of wooden studs or blocks B and B disposed at spaced positions on the frontal face of said back plate and which may be secured by any suitable means, such as the 75 bolts C. A hole D through each of the studs and the back plate, constitute suitable openings through which lag screws 1 are passed and screwed to the wall or other object or support 2. Formed integral with the top edge 80 of the back plate is a continuous longitudinal tongue A¹ having beveled upper edge A². The faces A³ of the edge of the back plate and at the bottom of said tongue, are inclined 85 downwardly, as shown in Figure 4. It is obvious that when the table top is at the extended position, the tongue and groove will have made close inter-engagement, thus rendering impossible any strains at the hinges when the table top will be under load. 90

The table top E which may be made of poplar, fir, birch, or any kind of stout wood, and which is about thirty six inches in length, is provided with a longitudinal groove E¹ near its rear edge, and which said groove 95 registers with and snugly engages the tongue A¹ of the back plate, when the table top is moved to the extended position. Hinges F and F which connect the table top to the studs B and B are so positioned on the underside 100 of the table top, that when the table top is in the extended position, the margin of the

underside of the table top and the groove E^1 thereof, are in registration with the top edge of the back plate and the tongue A^1 thereof, respectively. In tables of the smaller sizes, 5 the hinges F and F' are ordinary; in the larger sized tables, say from thirty six inches or more, in length, hinges of loose pin type are preferred. At a position substantially central of the back plate, there is secured an abutment 10 element against which the leg of the support bracket is adapted to rest. This abutment element consists of a vertically disposed bar G of the suitable thickness shown in Figure 3 and Figure 7. The frontal top portion has round- 15 ed edge G^1 to provide clearance for the table top in its swinging on the hinges F . The lower portion of this bar G has frontal concave face G^2 . Connected by hinges H and H' to the underside of the table top, is a stout 20 support bracket having the support leg J , and the forward portion of the bracket being provided with hand-hold K . The lower portion of the rear face of the bracket leg J has a slightly convex face J^1 , to correspond with the 25 slightly concave face G^2 of the abutment bar, as shown in Figure 7. The exterior finish applied to the surfaces of the several parts, and the ornamentalations of same, is variable according to the uses intended for the table. 30 My improved collapsible table is secured to the wall or other solid support, by inserting and securing the lag screws 1; thereby holding and securing the back plate rigidly at the desired location and height. The several 35 parts of the invention are so constructed, combined and arranged, that in the folded or collapsed status, as shown in Figures 5 and 6, the device complete, occupies relatively a very small space, the bracket occupying the 40 space between the back board and the table top. The manipulation of the device for making use of same is extremely simple. In the swinging of the table top from the vertical position, as shown in Figure 5; to the ex- 45 tended or horizontal position, as shown in Figure 3; the bracket, simply by force of gravity is swung downwardly, the edge of its leg lying against the edge of the abutment bar, and gradually coming to 50 alignment therewith. When the table top will have been brought up to horizontal position, the operative by a slight pressure toward the left, on the hand hold K , causes the bracket leg to complete its engagement with 55 the abutment bar, and in which such engage- 60 ment the concave face G^2 of said bar, holds the convex face J^1 of the bracket. By this arrangement, this table construction is ren- 65 dered rugged and dependable, under all strains to which the table is subjected. By this invention, the table top extends completely to the edge of the wall. By having the tongue and groove connection between the table top and the back plate, it is obvious 65 that the table is not only greatly strengthened

but there is such closure over the back plate that articles from the table top may not get upon or behind the back plate. The faces A^2 inclined downwardly from each side of the base portion of the tongue A^1 , of the back 70 plate overcome any tendency of dirt or foreign particles to accumulate at or near said tongue, and the coengagement between the edge of the table top and the back plate at the tongue and groove connection is of such effect 75 that any looseness or yielding at the hinges is prevented. Close fitting engagement is assured on account of the proper dimensioning of the tongue and groove in cross section, and by providing the bevel A^2 on the tongue, 80 there is free clearance when the table top is swung on its hinges.

I am aware that minor changes and modifications may be made in the structural and detail features of this invention, within the 85 scope of same as defined by the appended claims, without departing from the spirit of the invention or sacrificing any of its advantages.

What I claim as my invention, and desire 90 to secure by Letters Patent, is—

1. A collapsible table of the kind described, comprising a back plate, a table top having its rear marginal portion to engage the top edge of the back plate when the said table 95 top is in the extended position, hinge connections between the back plate and the table top whose axes are at spaced distance from the face of the back plate, a bracket hinged on the underside of the table top at an angle 100 and at a distance from the plane of the face of the back plate, and an upright abutment bar secured to the back plate, and having a recessed face to engage the leg of the bracket and to limit the distance through which it is 105 swung as the table top is moved to its ex- 110 tended position.

2. A collapsible table of the kind described, comprising a back plate having a continuous longitudinal tongue on its upper edge, stud 110 blocks on the face of the back plate near its ends, a table top having a continuous longitudinal groove on the underside of its rear edge adapted to engage the tongue of the back plate, hinge connections between the table top and the said stud blocks so adapted that when the table top is in extended position, the said tongue and groove are engaged, an abutment element on the back plate, and a bracket hingedly secured to the underside 115 of the table top, adapted to swing to position engaged with the abutment element when the table top is moved to the extended position.

3. In a device of the kind described, the 125 combination with a back plate having stud blocks on its frontal face and whose top edges are flush with the top edge of the back plate, hinge connections between said stud blocks and the underside of the table top and whose 130

axes are coincident with the tops of said stud blocks, a bracket hinged on the underside of the table top at a right angle to its longitudinal edge its vertical leg being at a distance from the axis of the table top hinge connections, not less than the measure of the thickness of the said bracket, and an abut-

ment bar secured on the face of the back plate adapted to become engaged by the vertical leg of the bracket when the table top is moved to the position extended at a right angle to the said back plate.

BLAINE F. GOODRICH.
